(57) **CLAIM**

The ornamental design for a compressible pelvic floor muscle exerciser, as shown and described.

DESCRIPTION

FIG. 1 is an isometric view of the compressible pelvic floor muscle exerciser showing my new design;

FIG. 2 is front elevational view thereof, the rear elevational view being a mirror image thereof;

FIG. 3 is a top plan view thereof, the bottom plan view being substantially identical thereto;

FIG. 4 is a right side elevational view thereof; and,

FIG. 5 is a left side elevational view thereof.
